UNITED STATES PATENT OFFICE.

CHARLES L. VOSE, OF WESTERLY, RHODE ISLAND.

DESIGN FOR AN ENVELOP-SEALER.

SPECIFICATION forming part of Design No. 33,097, dated August 21, 1900.

Application filed April 30, 1900. Serial No. 15,007. Term of patent 7 years.

To all whom it may concern:

Be it known that I, CHARLES L. VOSE, a citizen of the United States, residing at Westerly, in the county of Washington and State of Rhode Island, have invented a certain new and useful Design for an Envelop-Sealer, of which the following is a specification, reference being had therein to the accompanying drawings.

Figure 1 is a front elevation, and Fig. 2 a side elevation, of a manufactured article embodying the shape or configuration of my design.

A indicates the base portion of my design, showing externally the segment of a spheroid. From the center of the segment A extends the cylindrical stem or spindle B in upward direction when the article is standing upright, as shown. The outward swell C extends in a curved direction from stem B, but presents a horizontal upper surface. The

stem D, of less diameter than stem B, terminates in what may be called a "ball" K, although this ball or sphere is not complete. The parts F F extend from the sides of the ball K, and the barrel-shaped part E extends partly above ball K and partly within the recess at the upper portion of said ball or sphere.

Having described my invention, what I claim as new, and desire to secure by Letters Patent, is—

The design for an envelop-sealer, substantially as shown and described.

In testimony whereof I affix my signature in presence of witnesses.

CHARLES L. VOSE.
